UNITED STATES PATENT OFFICE

HARLEY H. WOLFE, OF DAYTON, OHIO, ASSIGNOR TO THE DAYTON PUMP & MANUFACTURING COMPANY, OF DAYTON, OHIO, A CORPORATION OF OHIO

DESIGN FOR A METER PUMP CASING

Application filed April 4, 1930. Serial No. 35,182. Term of patent 14 years.

To all whom it may concern:

Be it known that I, HARLEY H. WOLFE, a citizen of the United States, residing at Dayton, in the county of Montgomery and State of Ohio, have invented a new, original, and ornamental Design for a Meter Pump Casing, of which the following is a specification, reference being had to the accompanying drawings, forming a part thereof.

In the accompanying drawings:

Figure 1 is a front elevation of the pump casing showing my new design;

Figure 2 is a top plan view thereof.

I claim:

The ornamental design for a meter pump casing, as shown.

HARLEY H. WOLFE.
